UNITED STATES PATENT OFFICE.

NELSON F. BECKWITH, OF OMRO, WISCONSIN.

IMPROVEMENT IN HEAD-BLOCKS.

Specification forming part of Letters Patent No. 122,215, dated December 26, 1871.

To all whom it may concern:

Be it known that I, NELSON F. BECKWITH, of Omro, in the county of Winnebago and State of Wisconsin, have invented certain new and useful Improvements in Head-Blocks; and I declare that the following is a full, clear, and exact description thereof, reference being had to the accompanying drawings, in which—

Figure 1 is a top plan view of my improved standard. Fig. 2 is a central vertical section of the same; and Fig. 3 is a front elevation.

Similar letters of reference in the several drawings indicate the same parts.

The principal difficulties encountered in sawing logs into boards are as follows, to wit: First, when a log has been reduced to such thickness that only sufficient material remains for one or two boards, it is almost impossible to hold it upright upon its edge against the standards upon the carriage during the operation of sawing. The liability of the log to thus turn or slip upon the head-blocks is greatly aggravated if its lower edge next to the standard is wavy or rounded off from any cause. For this reason, it is customary in all saw-mills to leave the last cut in the form of a thick plank, affording sufficient bearing-surface to prevent its turning upon the head-block. Two thicknesses of lumber are therefore sawed from the same log or cant. Secondly, the standards employed for saw-mill carriages are usually so constructed to hold the log that, when the latter is to be sawed entirely into narrow boards of the same thickness, the last two or three are liable to bend during the operation of sawing, varying thickness of each more or less, and producing thereby imperfect boards.

My invention has for its object to overcome these difficulties; and to this end it consists in constructing the standards with wide-bearing faces for the logs, and in providing each with a central vertical slot or mortise, through which a series of hooks are projected to grasp the log or cant. The lower hook is curved upward to catch into the lower edge of the log next the standard, and the upper hooks are curved downward to catch into the face of the log. The lower hook and the series of upper hooks, therefore, move in opposite directions to grasp the log between them and prevent it from slipping. The hooks are operated simultaneously by a lever from the back of the standard, and by a suitable system

of connecting-bars, as I will presently describe. By this arrangement the upper hooks hold the log securely in contact with the lower hook, while the latter holds it firmly against the standard and prevents it from slipping until the last board is sawed. By constructing the standards with a wide face, and in arranging the hooks to project through a central slot, a broad bearing is formed for the log upon each side of the hooks, so that when the log is reduced to the thickness of two or three boards, the latter are held securely against bending while being sawed.

In the accompanying drawings, A is the standard, constructed with a wide face, B, and adapted to be applied to a carriage in the usual manner. C D are the hooks, pivoted in the same vertical line to the side of a metal plate, K, as shown, and arranged to be projected through a vertical slot, E, formed centrally in the wide face B of the standard. The plate K is set off from the side of the standard to a distance about equal to the width of the slot E, so as to form a continuation of said slot, as well to afford a protecting case for the hooks and their attachments as to afford proper supports for the same. The points of the hooks C are curved downward, and their inner ends are pivoted to a common connecting-bar, F. The lower hook D is pivoted at the angle of the standard, with its point curving upward. G is the operating lever, pivoted to the plate K at h, midway between the hook D and the lower one of the series C. The hook D is connected to the short arm of the lever by the pivoted bar I, and the hooks C are connected to the lever upon the opposite side of its pivot h by means of the bar J, which is either pivoted to the lower hook of the series C or to the connecting-bar F. I have thus far described the hooks and their attachments pivoted to the side of a plate, K; but that is not absolutely essential, as they may be pivoted directly to the side of the standard and the plate K dispensed with.

The operation is as follows: A log or cant is first laid upon the carriage in contact with the face of the standards, two or more of which may be employed, as preferred. The outer end of the operating lever is then raised, projecting the hook D upward through the slot E into the lower edge of the log, and the upper hooks C downward through the slot into its face. When the lever reaches the perpendicular, the respective points

f the connecting-bars F I J are in the same vertical line, or nearly so, and the hooks are therefore locked in place against the possibility of usual displacement. By this means the log is held firmly against the standards until the sawing is completed, the last board being held as securely as at the beginning of the sawing. I propose to construct the lower hook of sufficient strength to hold the log, in some cases dispensing entirely with the upper series, though preferably using both. To release the last board, it is only necessary to depress the lever which retracts the hooks behind the face B. In this position, as shown in Fig. 3, they are out of the way of the succeeding log laid against the standards.

While I have shown a standard specially constructed to receive the hooks I do not limit myself to this construction, as I design to apply them to all varieties of standards, old and new. Neither do I desire to limit myself to the precise arrangement of the operating lever, as it may be arranged to project the hooks when thrown down and to retract them when thrown up, which re-

sults are effected by transposing the ends of the bars I J upon the operating lever.

Having thus described my invention, what I claim as new is—

1. In combination with the standard for saw-mill carriages, the hooks C D, adapted to be simultaneously projected in opposite directions through the central vertical slot in the face of said standard, substantially as described, for the purpose specified.

2. The combination of the hooks C and connecting-bars F I, with the operating lever and the hook D, substantially as described, for the purpose specified.

3. The combination of the supporting guard-plate K with the slotted standard and the hooks C D and their attachments, substantially as described, for the purpose specified.

NELSON F. BECKWITH.
